Fig. 1

Fig. 2

Fig. 3

Fig. 4.

Fig. 5.

Fig. 6.

FIG. 1 is a side elevational view of a combined bowl support and stem for a tobacco pipe, showing my new design wherein the opposite sides of the stem are characterized by the identical combination of two slotted openings and one circular opening as are the top and bottom of the stem;

FIG. 2 is a top plan view thereof;

FIG. 3 is a bottom plan view thereof;

FIG. 4 is a side elevational view of a combined bowl support and stem for a tobacco pipe showing another form of my new design wherein the opposite sides of the stem are characterized by the paired groupings of three circular openings shown in contrast with the combination of two slotted openings and one circular opening on the top and bottom of the stem;

FIG. 5 is a top plan view thereof; and

FIG. 6 is a bottom plan view thereof.

I claim:

The ornamental design for a combined bowl support and stem of a tobacco pipe, as shown and described.
